AUTOMATIC TRAIN PIPE CONNECTER

Original Filed Dec. 5, 1919 2 Sheets-Sheet 2

Patented May 31, 1927.

1,630,582

UNITED STATES PATENT OFFICE.

JOSEPH V. ROBINSON, OF NEW YORK, N. Y.

AUTOMATIC TRAIN PIPE CONNECTER.

Application filed December 5, 1919, Serial No. 342,806. Renewed August 16, 1926.

My invention relates to automatic train-pipe connectors for railway cars and has among its objects to provide an improved support for such connectors in which the wear on the car coupler knuckle, and upon parts of the connector, may be compensated for by adjusting the base of the connector bracket longitudinally of the car coupler, and thus maintain a substantially constant degree of compression upon the supporting spring. A further object of my invention is to provide an improved means for properly positioning the bracket on the lug of the car coupler and for preventing back lash of the bracket with respect to the lug. A still further object of my invention is to provide an improved means for renewing defective gaskets between the faces of mated coupling heads while the cars remain coupled, while yet another object of my invention is to provide an improved universal joint for permitting free universal movement of the coupling head of the connector. Considerable difficulty has always been experienced in maintaining the supporting bracket of train pipe connectors in proper relation to the lug on the car coupler, and maintaining the proper spring compression on the coupling heads to insure a tight joint between the heads. In service, certain repairs and replacements must occasionally be made, and with the designs of supports heretofore employed it has been found difficult to make these without the use of an objectionable number of tools and men. With the use of but one tool one man can completely disassemble and assemble a pair of connectors having my improved supports without disconnecting the cars, the various moving parts being so designed and arranged that they may be readily removed while the cars remain coupled. In this fashion defective gaskets may be extracted from and new ones replaced between the faces of coupled connector heads without first uncoupling the cars.

Other novel features of my improvement will appear from the following specification and the drawings, in which—

Figure 1 is a side view of my improved support showing some of the parts in section.

Figure 2 is a longitudinal sectional plan view thereof showing some of the parts in section.

Figure 3 is a front elevation of my im-

proved support taken on the line 3-3 of Figure 1, and

Figure 4 is a detail plan view of the bracket A only, taken on the line 4-4 of Figure 3.

Referring now to the drawings: My improvement includes a bracket A comprising a member 5 and a base 6, the member being suitably secured to a lug 7 of the coupler 8, as by means of bolts 9. The member 5 is split vertically as at 10 to provide ears which facilitate clamping the same to the lug 7, and it carries at its lower end a hollow or perforated boss 11 extending axially of the car coupler. Below the lower face of the lug the member 5 is provided with a seat or way 12 to receive a wedge 13. The forward end of the way 12 is curved upwardly as at 14 to deflect the course of the wedge and cause the forward end thereof to follow around the corner 15 of the lug as the wedge is driven to the service position, and thus lock the wedge against accidental removal from such position. It will be observed that the wedge and the seat 12 are tapered so that as the wedge is driven home it produces a clamping action upon the bolts 9 and thus securely locks the member 5 to the lug 7 and prevents all back lash between the lug and the member, thus insuring correct positioning of the parts. With this construction, proper relation between the lug and the member is assured at all times. Should service develop movement between the lug and the member 5 it may be immediately eliminated by driving the wedge forward, which operation will draw the parts into firm engagement again.

The lower corners 16 of the member 5 form a seat adapted to mate with a complementary seat 17 on the base 6 of my improvement. The base comprises a vertically extending fork, the upper end of which terminates in a cylindrical portion 18 which, like the corners 16, is disposed in the horizontal plane and extends axially of the coupler and through the opening in the boss 11 of the member 5 as shown. A nut 19 secures the base in the boss 11, and constitutes means for adjusting the base longitudinally of the car and relatively to the member 5. Between the prongs 20 which form the fork of the base 6 I mount a pipe or hollow body member B having at its forward end a laterally diverging fluid conduit 21, and at its rear

end a perforated projection or flange 22, the conduit and the flange being connected by spaced walls or straps 23 formed preferably integrally with the flange and the conduit, though they may be otherwise connected therewith if desired. Within the hollow of said body I mount a universal joint comprising a tie rod 24 pivotally mounted upon the pivot bar 25, the pivot bar being in turn mounted in bearings 26 formed in the prongs 20 of the base 6. It will be observed that these bearings extend rearwardly of the prongs and fit within openings 27 at the sides of the flange 22, which construction, and the cooperation of the straps 23, and the tie rod and pivot bar 24 and 25 respectively, efficiently prevent undue rotation of the coupling head of the connector about its longitudinal axis and insures proper positioning of the coupling head and the body B with respect to the base 17. The tie rod has an elongated perforated head 28, having a forward inner face 29 which is flared in the horizontal plane and which rests in a complementary seat 30 formed at the center of the pivot bar 25. The tie rod extends from out of the hollow of the body B, through the opening in the flange 22, and to the rear thereof, and is provided with an elongated cylindrical portion 31, threaded to receive the abutment or nut 32, as shown. Upon the rear side of the flange I provide an annular seat 33 upon which I mount a suitable compression spring C, the spring being confined between the seat 33 and the abutment 32 and surrounding the tie rod 24. The function of the spring is to resiliently or flexibly support the coupling head D, and place it under pressure when the cars couple. Normally, the spring projects the coupling head a considerable distance in advance of the bracket A, with the flange 22 resting against the rear face of the base A. The flange is disposed vertically, and that portion thereof which lies above the bearings 26 is of greater length than that portion thereof which lies below said bearing, this in order to equalize the force required to move the head D downwardly with that required to move it upwardly from the normal uncoupled position. The fork of the base does not extend in exactly the vertical plane, but is disposed at an angle thereto, preferable of about two degrees, in order to throw the forward end of the body member B, and the coupling head D slightly above the horizontal center line of the bearings 26 of the prongs 20, to improve the coupling operation of the heads and eliminate jamming thereof. These bearings are open both at the sides and their forward face. They are curved or flared as shown to mate with the correspondingly shaped face of the ends 34 of the pivot bar 25. It will be observed that the plane of the rear side of the base

17 intersects the transverse center line of these bearings and intersects also the contacting faces of the tie rod 24 and the pivot bar 25 at the bottom of the seat 30 thru which they are pivotally connected.

In service the spring C acts to extend and place the coupling head D under pressure, as aforesaid. When two opposing connectors meet in the act of coupling the guides 35 of the coupling head D align the connectors, bringing their mating faces and parts into proper register. Further coupling movement of the cars will shift the flange 22 rearwardly away from the base 17 against the tension of the spring C, thus releasing the universal joint and permitting the heads to move freely in all directions, and instantly accommodating themselves to the sharp whipping motion of running cars without setting up any forces which tend to move the faces of the coupled heads one upon the other and destroy the joint between them. It occasionally happens that the gasket 36 in the face of the coupled heads requires replacement, and in order to accomplish this without first uncoupling the cars I thread the rear end of the tie rod 24 for a considerable distance as shown, and provide the nut 32 with an elongated shank 37 threadingly connected with the rear end of the tie rod as shown. With this construction the tension of the spring C may be relieved while the cars remain coupled. This is accomplished by backing the nut 32 off of the pivot tie rod, whereupon the spring C may be removed, the perforated head 28 of the tie rod 24 pushed forward carrying the pivot bar 25 forwardly out of its bearings 26, after which the body B may be lowered from out of the fork of the base A, and thus entirely remove the coupling head from the service position. The defective gasket may be then replaced with a new one and the parts re-assembled into the service position by retracing the operations thus just described. This feature of my invention is an improvement upon the gasket renewing means covered by my United States Patent #1,245,789, for improvements in automatic train pipe connectors, dated November the sixth, 1917.

Any suitable form of coupling head D may be used with my improved support, and may in any satisfactory manner be mounted upon the body B. I preferably threadingly connect the head with the forward end of the conduit 21 as shown, and provide the head with a port 38 in which is mounted a gasket 36, the gasket and the port having communication with the conduit 21. A section of the ordinary air hose 39 now universally in use on railway cars, connects the train pipe of the car with the conduit of my improvement, in any satisfactory manner. I have shown for this

latter purpose a standard form of fitting 40.

The various parts and members of my improvement are, of course, so proportioned and arranged that they will properly fit 5 with one another and fully allow the required free universal movement of the coupling head D. Inasmuch as the spring C acts upon the pivot bar 25 and maintains it in contact with the bearings 26 it may be 10 regarded as resilient means for maintaining the universal joint, comprising the tie rod 24 and the pivot bar 25, of my improvement in position, while the base may be described as having the outline of an inverted U, and hence as being an open end base.

What I claim as new and desire to secure by Letters Patent of the United States, is:

1. In an automatic train pipe connector, the combination of a coupling head, a base 20 having oppositely disposed bearings which project rearwardly from the rear side of the base, a universal joint mounted in said bearings for permitting universal movement to said head, a conduit connected with said coupling head, means extending from said conduit to the rear of said base, a projection mounted on the rear end of said means and cooperating with the rearwardly projecting portion of said bearings to resist 30 undue rotary movement of said coupling head about its longitudinal axis, and a spring for extending said head.

2. In an automatic train pipe connector, the combination of a lug, a coupling head, 35 a support for said head, said support comprising an upper member and a base, the upper member being secured at its upper end to said lug and having at its lower end a seat on which said base is mounted, and a screw means for adjusting said base along 40 said seat longitudinally of said upper member.

3. In an automatic train pipe connector, the combination of a lug, a coupling head, a 45 support for said head, said support comprising a member connected at its upper end to said lug and provided at its lower end with an elongated bearing disposed in the horizontal plane, a base provided with a horizontally disposed projection which extends into said bearing, a universal joint carried by said base, means on said projection for shifting said base longitudinally of said seat to vary the position of said joint relative to said member, and means 55 for preventing lateral movement of said base relative to said member.

4. In an automatic train pipe connector, the combination of a coupling head, a 60 spring for extending said head, a lug, and a support for said coupling head, said support comprising a member clamped to said lug and having at its lower end an opening, a vertically extending base having a horizontally disposed cylindrical projection ex-

tending in the direction of said coupling head and into said opening, a universal joint on said base, and means carried by said projection and engaging said member for adjusting said projection in said opening to vary the compression of said spring in service.

5. In an automatic train pipe connector, the combination with a car coupler having a lug, of a connector, and means for securing the connector to said lug, said means comprising a bracket connected with said lug, and a wedge device slidably mounted between the bracket and the lug for rigidly 70 securing the bracket to the lug, the front end of said device being bent to lock the same in service position.

6. In an automatic train pipe connector, the combination with a car coupler having a lug, of a connector, and means for securing the connector to said lug, said means comprising a bracket connected with said lug, a device mounted on said bracket and engaging the bottom of said lug relative to which lug the device is movable, and a 80 means for deflecting one end of said device as the device is forced into the service position.

7. In an automatic train pipe connector, the combination with a car coupler having a lug, of a connector, and means for securing the connector to said lug, said means comprising a bracket connected with said lug and having a bearing, a tapered device on 85 said bearing and engaging the lower face of said lug for drawing downwardly on the connection between said lug and said bracket, and means for locking said device in place.

8. In an automatic train pipe connector, the combination with a car coupler having a lug, of a coupling head and a support therefor, said support comprising a bracket bolted to said lug and having a seat, a device mounted on said seat and engaging the underside of said lug to exert a clamping action upon said bolts, and means on 100 said bracket for deflecting the course of said device as the device is driven to the service position.

9. In an automatic train pipe connector, the combination with a car coupler, of a coupling head and a support therefor, said support comprising a bracket connected to said coupler and having a seat, a wedge on said seat and adapted to be shifted along the same to take up the wear on the connection between said bracket and said coupler, the front end of said wedge being bent out of a straight line for locking said wedge in 115 the shifted position.

10. In an automatic train pipe connector, the combination of a lug, a coupling head, a support for said head, said support comprising two members, one of said members 130

- being secured at its upper end to said lug and having an opening in its lower end, the other of said members being adjustably mounted in said opening and closely fitting the same, means for adjusting said last mentioned member in said opening and holding the same against movement, and means carried by said last mentioned member for supporting said coupling head.
11. In an automatic train pipe connector, the combination of a lug, a coupling head, a support for said head, said support comprising two members, one of said members being secured to said lug at its upper end and having at its lower end an opening the axis of which extends parallel to the length of the car and the other of said members having a threaded portion mounted in said opening and closely fitting the same, and a nut on said threaded portion for adjusting the same relative to the first named member and holding the same against longitudinal movement in said opening, and means carried solely by said last named member for supporting said coupling head.
12. In an automatic train pipe connector, the combination of a lug, a coupling head, a support for said head comprising two members, one of said members being secured
- at its upper end to said lug and having at its lower end an opening, the axis of which extends parallel to the length of the car and which is arranged in a horizontal plane, the other of said members being adjustably mounted in said opening and closely fitting the same, means for adjusting said last named member in said opening and holding the same against movement relative to said first named member, and means carried by said last named member for supporting said coupling head.
13. In an automatic train pipe connector, the combination of a coupling head, a lug, a support for said head comprising a bracket, the upper end of which carries independent ears, a lug between said ears and having a lower face, a seat on one of said ears, a device interposed between the lower face of said lug and said seat and shiftable along the seat for exerting a clamping force in a vertical direction to securely lock said ears to said lug, and means for deflecting the course of said device to prevent accidental dislodgment of the device.

In testimony whereof I hereby affix my signature.

JOSEPH V. ROBINSON.
